UNITED STATES PATENT OFFICE.

HANS ADELMANN, OF NEW YORK, N. Y., ASSIGNOR TO HAM BOILER CORPORATION, OF NEW YORK, N. Y., A CORPORATION OF NEW YORK.

HAM BOILER.

Application filed May 5, 1924. Serial No. 711,146.

This invention relates to appliances for the cooking of hams or other meats in the piece or other food products in any bulk form, with provision for molding or compressing 5 the same during the cooking action.

Among the objects of the invention is to provide a cooking receptacle, referred to hereinafter for convenience as a ham boiler, having a receptacle or body portion, a cover 10 or closure for the receptacle, improved hand power fastening means between the closure and the receptacle, and with a resilient cushion means associated preferably with the cover to compensate for variations in bulk 15 during the cooking action, such as would result from either swelling or contraction of the commodity or the like, and to provide peculiar and novel means for attaching the fastening and handle means to the cover and 20 provide improved seats for the cushion devices.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference is had to 30 the accompanying drawings, in which like reference characters designate the same parts in the several views, and in which—

Figure 1 is a vertical sectional view approximately along the vertical central plane 35 of the device.

Fig. 2 is a plan view.

Fig. 3 is an end elevation.

Fig. 4 is a detail of a modification.

Fig. 5 is a plan view of the same.

Referring now more specifically to the drawings I show a receptacle 10 formed as by stamping or the equivalent from sheet metal of any suitable strong, rigid, non-corrodible material. This receptacle is shown, especially in Fig. 2, as of oval form but with substantially vertical walls and is provided around its upper open top with an outwardly projecting flange 11, said flange lying substantially in a horizontal plane except at the 50 ends where downwardly deflected lips 12 are provided.

The cover or closure 13 is substantially a flat member but having a downwardly turned marginal flange 14 which is adapted 55 to move downward fairly close to the in-

ner surfaces of the receptacle walls. The main portion of the cover is substantially flat and imperforate, a form best calculated for ready, easy, and relatively cheap construction from sheet metal as by stamping. 60

15 indicates a handle or bar of any suitable material or construction as, for instance, a casting having forks 16 at its ends and having formed along the lower surface not far from the respective ends a pair of bosses 65 17 forming seats, and these bosses are provided with central vertical holes 18 which merge into counter bores 19 at the top of the bar. 20 indicates a pair of catch members in the nature of racks which may be formed 70 in any convenient manner and each having at its upper end a knuckle portion 21. Each catch 20 is suspended by a pivot pin 22 passed through the spaced lugs 30 of a yoke shaped hand power lever 31, said lugs 30 in 75 turn being pivoted on pins 32, eccentric to the pin 22 and attached to the ends of the fork 16. In the open position of the parts the levers 31 are directed upward as in dotted lines of Fig. 1 and with the rack pivots 22 below the pivots 32. When the levers 31 are then swung outward from each other and downward the pivots 22 are swung around or past the vertical plane of the pivots 32, 80 relatively, insuring that the levers 31 will be 85 self retained against the racks and with the springs under sufficient compression for the purpose of the device. The racks are afforded a sufficient degree of tilting around the respective lips 12 to enable the aforesaid 90 relative movement or interchange of position of the two sets of pivot pins.

In the modified form of Figs. 4 and 5 the levers 31^a swing upward and toward each other into locking and holding position. 95 Otherwise the action is substantially the same in both arms. The ends of the bar, however, are in the form of simple knuckles 16^a instead of forks as above described, and the upper end portion of each rack 20 consists of a pair of spaced lugs 21^a instead of a simple knuckle 21.

A pair of springs 24 are shown interposed between the bar 15 and the cover 13 to afford the desired resiliency or cushioning effect 105 above referred to. The upper ends of the springs are seated upon or around the bosses 17 while the lower ends of the springs are seated upon or around a pair of housings 25.

Each housing 25 consists of a hollow boss 110

25^a for the reception and accommodation of a nut 26 within it, and integral with the boss 25^a is a horizontal flange 25^b. These housings are readily formed from sheet metal by 5 stamping or the like and the material thereof is of such a nature as to be readily and directly connectible to the upper surface of the cover 13. As shown at 27 the preferred manner of securing the housings 25 to the 10 cover is by direct welding of the flanges to the cover. This may be by any suitable process such as spot welding, acetylene welding or its equivalent, but in any event the connection is strong, rigid, and permanent, and the nut 26 is then retained within 15 each dome or boss 25^a. The boss 25^a is preferably formed as a counter part of the form in plan of the nut, shown as hexagonal, so as to hold the nut from rotation. Within 20 the center of the top of the boss is formed a smooth hole 25^c. The attachment means between the bar 15 and the cover connections are shown as consisting of a pair of bolts 28 whose lower threaded ends project 25 freely through the holes 25^c and have threaded engagement within the nuts 26 while the extreme ends thereof bite snugly against the original surface of the cover below the nuts, thereby locking the bolts rigidly in place as anchored by the bolt nuts. 30 The upper shoulder portions of the bolts have slideable movement in the holes 18 of the bosses 17 while the heads normally are depressed within the counter sinks 19. 35 When, however, the bar is depressed forceably with relation to the cover, compressing the springs 24, the head ends of the bolts may project upward somewhat above the normal position. Thus I provide by means of the 40 housings 25 and the parts co-operating therewith a substantially permanent connection between the bar and the cover and with interposed cushions, such connections, however, being removable or interchangeable in 45 the event of necessity at any time by the use of tools, although the housings are retained as rigid fixed parts of the cover.

In operation a ham or its equivalent after being "made" or prepared is put directly 50 into the receptacle, and the cover being manipulated by the handle or bar 15, is put

directly upon the ham, the operator bringing downward upon the ends of the bar only about enough force to insure temporary holding of the catch members upon the lips 55 12. Then the levers 31 are swung around their pivots 22 and 32, according to the construction or manner of hanging the racks above described, bringing the pivots 22 past the dead centers of the pivots 32 and insuring the proper degree of compression of the ham within the receptacle. It will thus be seen that a very moderate amount of force applied to the levers 31 will insure ample compression of the springs and ham and 60 such compression will react in such a manner with respect to the two sets of pivot pins as to insure self locking of the parts. The levers, however, are easily swung to unlocking position when the cover is to be removed. 70

I claim:

1. In a ham boiler, the combination of a metal cover, a handle spaced above the cover, and connections between the cover and the handle comprising a bolt extending from the handle to the cover and having its cover end threaded, a metal housing welded to the cover and having a hollow boss with a hole therethrough through which the threaded end of the bolt projects, and a nut housed 80 within the boss and having threaded interlocking engagement with the end of the bolt, the threaded end of the bolt having biting engagement directly with the surface of the cover within the housing. 85

2. In a ham boiler, the combination with a receptacle and a cover movable within said receptacle to compress the contents thereof, of combined power application and locking means for said cover comprising a handle 90 and a lever having pivotal engagement with the handle, and a hook having direct eccentric pivotal engagement with said lever and extending downwardly into engagement with the receptacle, whereby when said lever 95 is swung about its pivot to lie along the top of the handle and in locking position, a downward force is exerted upon said cover to depress the same into the receptacle and to lock it in position. 100

In testimony whereof I affix my signature.
HANS ADELMANN.
